UNITED STATES PATENT OFFICE.

EMIL MATTMAN, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

DYNAMO-ELECTRIC MACHINE.

No. 891,847.

Specification of Letters Patent.

Patented June 30, 1908.

Application filed August 31, 1906. Serial No. 332,777.

To all whom it may concern:

Be it known that I, EMIL MATTMAN, citizen of the Republic of Switzerland, residing at Norwood, in the county of Hamilton and 5 State of Ohio, have invented certain new and useful Improvements in Dynamo - Electric Machines, of which the following is a full, clear, and exact specification.

My invention relates to multipolar dynamo 10 electric machines and particularly to the cross-connectors of the brush-holders.

In multipolar dynamo-electric machines, the brush-holders carrying the positive and negative brushes are usually connected together 15 respectively by two ring-shaped strap copper cross-connectors arranged side by side. These cross-connectors are supported only by the strap conductors connected to the brush-holders.

20 In machines of considerable diameter it has been found that the cross-connectors are inadequately supported and braced and tend to become distorted by their own weight, thus marring the appearance of the machine and 25 rendering liable a short-circuit by the cross-connectors coming into contact with each other. Also there is danger of the strap conductors being loosened or otherwise injured by the constant vibration.

30 The object of my invention is to space apart and clamp the cross-connectors rigidly in position so that they are held a predetermined distance apart and so that there is no 35 danger of the cross-connectors being distorted or seriously vibrated.

In carrying out my invention I provide 40 between the cross-connectors a plurality of spacing members and tightly clamp the spacing members and cross-connectors together.

More specifically considered my invention 45 consists in arranging between the adjacent strap cross-connectors a plurality of insulating spacing members and clamp the spacing members and cross-connectors together by 50 means of U-shaped members and tightening bolts. The clamps are thus adjustable so that the same clamps can be used on cross-connectors consisting of different numbers 55 of layers of strap copper.

My invention still further consists in the 60 details of construction and the combinations and arrangements of parts described in the

specification and set forth in the appended claims.

55

For a better understanding of my invention reference is had to the accompanying drawings in which

Figure 1 is a partial end elevation of a 60 dynamo-electric machine equipped with my invention; Fig. 2 is a sectional elevation slightly enlarged, of the commutator end of the machine, parts being omitted for the sake of clearness; Fig. 3 is an enlarged elevation of one of the cross-connector clamps 65 showing also a portion of the cross-connector; Fig. 4 is a sectional view taken at right angles to the view shown in Fig. 3, the cross-connectors being in section and the clamps and spacing member for the cross-connectors 70 being in elevation; and Fig. 5 is a view similar to Fig. 4 showing the cross-connectors consisting of a number of layers of strap copper.

Referring now to the figures of the drawing, 75 10 represents a shaft of a dynamo-electric machine on which is mounted a commutator 11 and armature 12. The field member surrounds the armature, and consists of a field frame or yoke 13 having inwardly extending 80 field magnets 14. At the commutator end of the machine are a number of rollers 15 which support a brush yoke 16 consisting in this case of an outer ring 17, inwardly extending arms 18, and an inner ring 19. Mounted on 85 the inner ring 19 are a plurality of brush forks 19^a which carry the commutator brushes. The positive and negative brushes are connected together by the usual strap copper cross-connectors 20 arranged side by 90 side, all the brush-holders supporting the positive brushes being connected to one cross-connector and the brush-holders supporting the negative brushes being connected to the other cross-connector by copper straps 95

21. Each cross-connector consists of one or more rings of strap copper, a large number of rings or layers being provided for heavy current machines. In some machines the cross-connectors consist of strap segments of 100 gradually increasing lengths, so that the cross-connectors gradually increase in thickness from the outer end to the end connected to the cable and carrying the heaviest current. The copper straps are bound together 105 by cord or tape 22 as shown in Figs. 4 and 5.

In order that the cross-connectors may not be distorted by their weight or seriously vibrated, I space the cross-connectors apart and clamp them together in engagement with the spacing members. In this case I provide between the cross-connectors at intervals spacing members of insulating material 23, in this case, blocks of wood, and clamp the spacing members and cross-connectors tightly together. Each clamp consists, in this instance, of two U-shaped members 24 having perforated outwardly extending ears 25 and bolts 26 which extend through the perforated ears so as to draw the U-shaped members tightly together. The clamping members which are preferably of metal are separated from the cross-connectors by the suitable thickness of insulation 27 such as fish-paper. In this case each U-shaped clamping member is provided on opposite sides with fingers or lugs 28 which extend over the ends of the spacing blocks and prevent displacement of the spacing members.

It is seen that the clamping members are adjustable and can be applied to cross-connectors of different thicknesses. For example in Fig. 4 each cross-connector consists of one layer or section of copper and in Fig. 5 each cross-connector consists of four layers. The same clamps are employed in each case except that longer bolts 26^a are substituted for the shorter bolts 26 of Fig. 4. Thus it is unnecessary to carry in stock a large number of castings or patterns. All that is necessary is to provide different sizes of clamping bolts.

When the cross-connectors are braced and clamped together as shown there is no danger whatever of the cross-connectors being distorted, or vibrated, or of a short-circuit occurring on account of the cross-connectors coming in contact with each other.

It is evident that many modifications can be made in the details without departing from the spirit and scope of my invention and I aim in my claims to cover all such modifications.

What I claim as new and desire so secure by Letters Patent is:—

1. In a dynamo-electric machine, a plu-

rality of brush-holders, supporting means for said brush-holders, cross-connectors between the brush-holders, spacing members between the cross-connectors, and means independent of the brush-holders and separate from said supporting means for clamping the cross-connectors and spacing members together. 55

2. In a dynamo-electric machine, a plurality of brush-holders, strap cross-connectors connected to the brush-holders, a plurality of insulating spacing members between the strap cross-connectors, and clamps extending around the cross connectors for fastening the cross-connectors and spacing members together. 60

3. In a multipolar dynamo-electric machine, a plurality of brush-holders, a pair of strap cross-connectors for the brush-holders, spacing members between the cross-connectors, and adjustable clamping members extending around the cross connectors for fastening the cross-connectors and spacing members together. 65

4. In a multipolar dynamo-electric machine, a plurality of brush-holders, a pair of adjacent strap cross-connectors for the brush-holders, a plurality of insulating spacing members between the cross-connectors, and a plurality of clamps around the cross-connectors, each clamp comprising a pair of U-shaped members and bolts for drawing the said U-shaped members tightly together. 70

5. In a multipolar dynamo-electric machine, a plurality of brush-holders, a pair of adjacent strap cross-connectors for the brush-holders, a plurality of insulating spacing members between the cross-connectors, and a plurality of clamps around the cross-connectors, each clamp comprising a pair of U-shaped members having outwardly extending perforated or slotted ears and bolts passing through said ears, for drawing said U-shaped members together. 85

In testimony whereof I affix my signature, in the presence of two witnesses.

EMIL MATTMAN.
